UNITED STATES PATENT OFFICE.

MORRIS LEON AND ALPHA B. VANCE, OF FORT SMITH, ARKANSAS; SAID VANCE
ASSIGNOR TO SAID LEON.

DISPLAY-STAND.

1,255,444.

Specification of Letters Patent.

Patented Feb. 5, 1918.

Application filed September 14, 1916. Serial No. 120,149.

To all whom it may concern:

Be it known that we, MORRIS LEON and ALPHA B. VANCE, citizens of the United States, residing at Fort Smith, in the county of Sebastian and State of Arkansas, have invented certain new and useful Improvements in Display-Stands, of which the following is a specification, reference being had therein to the accompanying drawing.

10 This invention has reference to display devices that include a platform arranged to be supported, when desired, by a T-stand to hold shoes, boxes, etc., of a more rigid nature than fabric articles that can be draped over such stands, a holder of this general type being disclosed by our copending application for Letters Patent on improvements in display-holders, filed March 11, 1916, Ser. No. 83,524.

20 It is an object of the present invention so to form such a holder that it not only can be placed on and be supported by such a stand, but also may be attached conveniently to and be supported by other supports and be readily removable therefrom.

When read in connection with the description herein, the details of construction and arrangement of the parts contemplated by the invention will be apparent from the accompanying drawing, forming part hereof, wherein an embodiment of the invention is disclosed, for purposes of illustration.

Like reference-characters refer to corresponding parts in the views of the drawing, 35 of which—

Figure 1 is a side view of the holder on a stand;

Fig. 2 is a view of the holder on a molding or the like;

40 Fig. 3 is a view of the holder supported by a fixed headed member; and

Fig. 4 is a back view of the holder.

Having more particular reference to the drawing, A designates a base, B a standard, 45 and C a cross-piece of a T-stand such as is commonly used for display purposes in stores and elsewhere for display of fabric articles that may be draped over the cross-piece; D designates a fixed substantially horizontal member, such as molding; and 50 E designates a fixed substantially vertical member, such as a piece of paneling, having extending therefrom headed members F, such as tacks, nails, screws, or the like.

It frequently is desired to display, in connection with articles that can be draped, others that, because of their character, cannot be draped or otherwise conveniently attached to a T-stand of ordinary form, such, for example, as hosiery and shoes, which often are sold together and sometimes are required to match in color, and this invention is designed to meet this demand in a practical and simple manner, and at the same time to provide a holder that is adapted to be used independently of such a stand, as well as with it.

For this purpose, the invention provides a holder that includes a platform 5, which preferably is made of sheet metal, but which also may be made of wood or other suitable material. The platform has at its normal lower end a flange 6 extending upwardly with respect to the surface of the platform and which may be formed by bending when pliable material is used for the platform, this flange being for the purpose of retaining articles on the platform when it is in an inclined position. The platform has in its upper portion at a place removed from its upper end a hook or other suitable projection 7 at each side adapted to engage a horizontal member such as the cross-piece C of a T-stand, and when the platform is made of pliable material the hooks or projections may be formed by slitting and bending the material.

Near the portion of the platform that is normally the lower there is hinged on the back thereof an arm 8, having at its free end 90 an indentation or seat 9 arranged to embrace an upright member such as the standard B of a T-stand, so that, when the hooks or projections 7 are engaged with a cross member, the arm will act as a strut to maintain the platform at an inclination, as shown by Fig. 1. The arm 8, if desired, is made of two pieces overlapping each other and slideable one with respect to the other, and these pieces are held adjustably together by a clamp 10 whereby the arm may be made longer or shorter and the inclination of the platform thereby altered as desired. In order to keep the arm 8 outstanding from the back of the platform, so that it is in position 95 for engagement with a standard or other part, and to keep it from swinging against the platform when the device is used inde-

pendently of a stand or the like, a strut 11 is hinged at or near the free end of the arm and arranged to contact with the upper surface of the platform at a place removed from the connection of the arm and platform, and the free end of the strut may be held in engagement with the platform by a hook or other projection 12, which may be formed by bending out of the material of the platform when the material is pliable. The hinged connections of the arm with the platform and strut permit those parts to be folded against the platform when desired. The strut serves to support the upper part of the platform when the holder is placed on a counter or the like.

An opening 13 is formed in the upper portion of the platform to permit a standard or other similar upright support to project therethrough when there is no cross-piece on the standard or when it is desired to place the holder below a cross-piece. In order to enable the platform thus to be placed without removing a crosspiece or other projection, a slot 14 extends from its edge to the opening to accommodate the upright while the platform is being placed on or removed from it.

In order to enable the holder to be associated with a cross-piece of a T-stand at a lower place than when the hooks or projections 7 engage that member, the upper end of the platform is formed with a down-turned flange 15 preferably disposed at an acute angle with respect thereto, and formed by bending the upper end portion of the platform when it is of pliable material. The flange is arranged to engage over the cross-piece, and the arm 8 then engages the standard and maintains the platform at an inclination, as shown by Fig. 1. In like manner, the flange may be employed in supporting the platform on a molding or the like, as shown by Fig. 2, in which case the flange engages over the molding or the like and the free end of the arm 8 seats against a wall

or the like below and maintains the platform at the desired inclination.

The flange 15 is formed with a slot 16 extending upwardly from its lower edge and adapted to receive a headed member, such as a tack, nail, screw, or the like F, whereby the platform may be supported as shown by Fig. 3. In this case the head of the member F by overlapping the edges of the slot 16 may maintain the platform at the proper inclination; or, of course, the free end of the arm 8 by contact with the panel, wall, or other part below the member may maintain the desired inclination as in the other modes of use of the platform. In any of these cases, the length of the arm 8, and thereby the degree of inclination of the platform, may be altered by loosening the clamp 10 and moving the parts with respect to each other and then tightening the clamp.

Having thus described our invention, what we claim as new, and desire to secure by Letters Patent, is—

A platform for display-holders formed of sheet metal and arranged to be maintained normally at an inclination with respect to a support, the material of the platform being bent upwardly at its lower end to form an article-retaining flange, bent downwardly at the sides intermediately of the ends to form projections for engagement with a supporting cross-piece, and bent downwardly at its upper end to form a flange for engagement with a supporting cross-piece, said flange having a slot for reception of a headed member, and there being in the platform between its ends an opening for reception of an upright support, and an arm hinged to the lower portion of the platform and arranged at its free end to engage a fixed part.

In witness whereof, we affix our signatures.

MORRIS LEON.
ALPHA B. VANCE.
